UNITED STATES PATENT OFFICE.

WILLIAM L. SCHELLENBACH, OF HARTWELL, OHIO.

LENGTH-STOP.

1,163,861.

Specification of Letters Patent. Patented Dec. 14, 1915.

Application filed June 14, 1915. Serial No. 33,934.

To all whom it may concern:

Be it known that I, WILLIAM L. SCHELLENBACH, a citizen of the United States, and residing at Hartwell, in the county of Hamilton and State of Ohio, have invented a new and useful Improvement in Length-Stops, of which the following specification is a full disclosure.

My invention relates to an automatic 10 length stop for engine lathes, or machine tools having a longitudinally moving feed member, whether it carries the work or tool.

One of the objects of the invention is to avoid a long stop bar, extending full length 15 of the bed, and also to provide means for supporting the stop bar from the carriage or feed member.

Another object of the invention is to support the stop bar from the apron, in position 20 to be engaged by an apron member. The stop bar is stationary normally, the carriage being slideable relative thereto, but the bar is moved with the carriage when the carriage engaging member hits the stop, the 25 movement of the stop bar being translated to unclutch the lead shaft from its driving member, and so automatically arresting the carriage feed.

The principle of the invention may be 30 variously modified or adapted to different specific embodiments.

It is a further object to provide a specific modification of the step-like telescoping stop dogs.

35 The features will be understood in connection with the description of the accompanying drawings, forming a part of this specification, and showing the principle of the invention as applied to the carriage and apron 40 of a conventional engine lathe, in which:—

Figure 1 is a front elevation of a lathe embodying my improved stop mechanism. Fig. 2 is an enlarged right hand elevation of the apron. Fig. 3 is a fragmentary front 45 elevation of a portion of the apron showing a modified form of stop dogs and abutment lever.

In the drawings, 1 represents the lathe bed having the usual V-ways upon which the tool carriage 2 slides. Depending from the front edge of the carriage is the apron 3 inclosing the transmission gear train. This gear train

transmits motion from the lead shaft 4 through the beveled gear and pinion 5, 6, the reducing gears 7, 8, 9, 10, to the rack pinion 55 11 which meshes with the stationary rack 12 and propels the tool carriage.

The lead shaft 4 is driven by the gears 13, 14, the gear 13 meshing with the head-stock spindle gear 15. The gear 14 is loosely journaled on the lead shaft and is provided with clutch teeth 16 which intermesh with companion clutch teeth of a clutch collar 17 fixed to the lead shaft. The lead shaft 4 is slidably mounted in brackets 18, 19, secured to 60 the lathe bed and is normally shifted toward the right, with the clutch teeth in driving engagement, by the spring 20, said spring being interposed between the bracket 18 and a collar 21 fixed on the shaft. 70

It will, of course, be understood that the shaft 4 has the key slot 22 extending throughout the major portion of its length and that the beveled pinion 5 is keyed thereto as is the usual practice in this type of lathe. 75

The mechanism utilized for shifting the lead shaft to unclutch the driving gear 14, and thereby arrest the travel of the tool carriage, consists of a stop bar 25 slidably supported in a grooved bracket 26 detachably 80 bolted to the under surface of the apron, said bar having a dove-tailed upper surface to which is secured a series of stop dogs 27. These dogs are preferably of the well-known telescoping type and are coördinately positioned on the bar relative to the particular duration and sequence of tooling operations to be performed. Secured to the left hand end of the stop bar 25 is a bracket 28 which extends upwardly and terminates with a collar 29 loosely surrounding the lead shaft 4 and normally engaging a collar 30 adjustably secured to said shaft. Said collar is adjusted laterally relative to the maximum carriage travel necessary for a given piece of 90 work and to permit such adjustment independently of the stop bar, I provide a beveled nose spring detent 35 seated within the bracket 28 and engaging the beveled end 30' of the collar. The opposite end of said collar is also beveled to permit the detent to ride over said collar when the stop rod assumes its normal position, as shown, after a readjustment of the collar. 95

100

Coacting with the stop dogs 27, during the travel of the carriage, is an abutment lever 31 which is pivoted at 32 on an upward extension of the bracket 26, said lever being provided with a hand grip 33 by which it is manually lowered or raised into and out of engaging alinement with the several stop dogs 27 during the travel of the carriage.

Previous to starting the lathe, the stop dogs are selectively set on the stop bar at points determined by the length of the different cuts to be made on a given piece of work. The machine is then started and the carriage travels toward the head-stock until the abutment lever contacts with the first stop dog 27. The abutting of the abutment lever 31 against the stop dog will translate the stop bar 25, and with it the lead shaft 4 to the left, thereby unclutching the clutch collar 17 from the clutch teeth 16 of the gear 14. This discontinues the feed of the lead shaft and stops the carriage. The abutment lever is then raised out of engagement with the first stop dog and the spring 20 automatically restores the stop bar and lead shaft to normal position, and again throws in the clutch to restart the carriage feed. When the abutment lever contacts with the second stop dog, the same unclutching operation is repeated. The collar 21 may abut the bracket 18 to form a stop for the lateral shift of the lead shaft.

The modification shown in Fig. 3 shows stop dogs of different height coöperating with a stepped abutment plate 31' secured to the abutment lever. Each of the steps of this plate can be raised out of alinement with its companion stop dog without disaligning the next step with its companion stop dog.

40 I claim—

1. In a machine of the class described, a bed, a longitudinally reciprocating feed member thereon, a feed shaft on the bed, means actuated by said shaft for feeding said member, and a clutch controlled driver for said shaft, a stop bar supported by said feed member, means holding said bar normally in stationary position, a stop-engager on the feed member, and means for translating motion imparted to the bar through the stop-engager to operate said clutch and arrest the feed of said member.

2. In a machine of the class described, a bed, a longitudinally reciprocating feed member thereon, a feed shaft on the bed, means actuated by said shaft for feeding said member, and a clutch controlled driver for said shaft, a slide-way supported on said feed member, a stop-bar suspended on said slide-way support parallel with said shaft, means for normally holding said bar stationary while the feed member is in motion, a stop-engager on the feed member, and connection between said bar holding means and 65 said clutch control for operating the clutch

when the bar is moved by the stop-engager to the feed member.

3. In a device of the class described, a bed, a longitudinally reciprocating feed member thereon, a longitudinally shiftable feed shaft on the bed, means actuated by said shaft for feeding said member along the bed, a clutch controlled driver for said shaft, a coacting clutch member actuated by the shifting of the feed shaft, a slide-way support on the feed member, a stop bar suspended in said support parallel with the feed shaft, a device on the feed shaft and longitudinally movable therewith for holding said bar normally stationary while the feed member is operating between stop points, and a stop-engager on said feed member adapted to move the stop bar, feed member and feed shaft in unison to unclutch the feed shaft at predetermined points in the path of motion of the feed member.

4. In a device of the class described, a bed, a longitudinally reciprocating feed member thereon, a longitudinally shiftable feed shaft on the bed, means actuated by said shaft for feeding said member along the bed, a clutch controlled driver for said shaft, a coacting clutch member actuated by the shifting of the feed shaft, a slide-way support on the feed member, a stop bar suspended in said support parallel with the feed shaft, a device on the feed shaft and longitudinally movable therewith for holding said bar normally stationary while the feed member is operating between stop points, means for adjustably securing the said device lengthwise of the feed shaft to determine the selective operative position of the stop bar, and a stop-engager on said feed member adapted to move the stop-bar, feed member and feed shaft in unison to unclutch the feed shaft at predetermined points in the path of motion of the feed member.

5. In a device of the class described, a clutch controlled feed member, a bar normally stationary relative to the movement of said feed member, but movable therewith at predetermined points to operate the clutch, a series of step-like stop dogs longitudinally adjustable on said bar, adapted to be brought into end to end and non-overlapping contact, and a stop-engager on the feed mechanism adapted to be adjusted into or out of position for dog engagement, said stop-engager having a series of stepped abutments corresponding to the stop arrangement of said dogs, each of said abutments being positioned to coact with its respectively stepped stop dog.

6. In combination with a carriage, apron and apron mechanism of an engine lathe, an automatic length stop comprising a stop-bar supported by the apron, said apron support and bar being arranged for relative slide movement, a stop-engager on the apron, 125

feed mechanism for the apron, means causing said stop-bar and stop-engager to intercept at predetermined points in the path of apron travel, and means actuated by said 5 interception rendering the apron feed mechanism inoperative.

In witness whereof, I hereunto subscribe

my name, as attested by the two subscribing witnesses.

WILLIAM L. SCHELLENBACH.
